(57) **CLAIM**

The ornamental design for an outlet plug plate as shown and described.

DESCRIPTION

FIG. 1 is a rear perspective view of an outlet plug plate, in accordance with an embodiment;

FIG. 2 is a front view of the outlet plug plate of FIG. 1; FIG. 3 is rear view of the outlet plug plate of FIG. 1; FIG. 4 is a left side view of the outlet plug plate of FIG. 1; FIG. 5 is a right side view of the outlet plug plate of FIG. 1; FIG. 6 is a top view of the outlet plug plate of FIG. 1; FIG. 7 is a bottom view of the outlet plug plate of FIG. 1; FIG. 8 is a rear perspective view of an outlet plug plate, in accordance with another embodiment;

FIG. 9 is a front view of the outlet plug plate of FIG. 8; FIG. 10 is rear view of the outlet plug plate of FIG. 8; FIG. 11 is a left side view of the outlet plug plate of FIG. 8; FIG. 12 is a right side view of the outlet plug plate of FIG. 8;

FIG. 13 is a top view of the outlet plug plate of FIG. 8; and, FIG. 14 is a bottom view of the outlet plug plate of FIG. 8. The ornamental design which is claimed is shown in solid lines in the drawings. All the broken lines shown represent portions of the outlet plug plate that form no part of the claimed design. Where the unequal length broken lines abut the shaded surface it is understood that those broken lines represent an unclaimed boundary between claimed and unclaimed surfaces.
